US00D387352S

United States Patent [19]**Kaneko et al.****[11] Patent Number:** **Des. 387,352****[45] Date of Patent:** ****Dec. 9, 1997****[54] REMOTE CONTROL**

[75] Inventors: **Steven T. Kaneko; Edwin Thorne, III,**
both of Seattle; **Scott Plank, Redmond,**
all of Wash.; **Rick Lewis, Palo Alto,**
Calif.

[73] Assignee: **Microsoft Corporation, Redmond,**
Wash.

[**] Term: **14 Years**

[21] Appl. No.: **51,909**

[22] Filed: **Mar. 19, 1996**

[51] LOC (6) Cl. **14-03**

[52] U.S. Cl. **D14/218**

[58] Field of Search **D14/218, 100,**
D14/114, 115; D10/106; D21/141.1; 340/825.22,
825.25, 825.72; 348/734; 359/142-148;
D18/6, 7

[57] CLAIM

The ornamental design for a remote control, as shown and
described.

DESCRIPTION

FIG. 1 is a top rear isometric view of a remote control
showing our new design;

FIG. 2 is a top plan view thereof;

FIG. 3 is a bottom plan view thereof;

FIG. 4 is a right elevational view thereof;

FIG. 5 is a left elevational view thereof;

FIG. 6 is a front elevational view thereof; and,

FIG. 7 is a rear elevational view thereof.
